UNITED STATES PATENT OFFICE.

ALBERT R. THOMPSON, OF SAN JOSE, CALIFORNIA, ASSIGNOR TO ANDERSON-BARNGROVER MFG. CO., OF SAN JOSE, CALIFORNIA, A CORPORATION OF CALIFORNIA.

PRESSURE-COOKER.

1,398,476.

Specification of Letters Patent. Patented Nov. 29, 1921.

Application filed December 6, 1920. Serial No. 428,556.

To all whom it may concern:

Be it known that I, ALBERT R. THOMPSON, a citizen of the United States, residing at San Jose, in the county of Santa Clara and State of California, have invented certain new and useful Improvements in Pressure-Cookers, of which the following is a specification.

My invention relates to that class of cookers used in the canning art, in which the treatment of the canned goods is carried out in a fluid-tight chamber under fluid pressure, generally of steam.

In pressure cookers of this type, especial attention is necessarily directed to the valves which control the entrance of the cans to, and their exit from the treating chamber, for the reason that such valves must not only handle the cans, permitting and effecting their introduction into the chamber and their discharge therefrom, but must also be of such a nature as to prevent the release of internal pressure by the escape and loss of the steam.

An approved type of valve used in this connection comprises a shell having separate communications with the cooking chamber and with the outer air, and a rotating valve member closely fitted in the shell and having a peripheral series of can-receiving pockets adapted to register successively with said communications, so that a can may be received from without and be delivered into the chamber, as in the case of the inlet valve, or the reverse, as in the case of the outlet valve.

It is obvious, however, that the inlet valve, as it drops a can from one of its pockets into the cooking chamber, receives in the emptied pocket, a given volume of steam from the chamber, and this steam is carried around to the outer air communication of the shell and there escapes and is lost. In the case of the outlet valve the escape and loss of steam is not so pronounced, because the outgoing pockets are practically filled by the cans. Consequently it has been proposed, in the case of the inlet valve to bypass the steam confined in pockets leaving the cooker-chamber communication, into the pockets approaching said communication, with the idea of carrying said steam back into the cooker. This, however, is not very effective for the obvious reason that the

pockets approaching the cooker chamber 55 communication are practically filled by the cans which they are carrying to said chamber and they have, therefore, but little capacity for the by-passed steam; so that even with this expedient the greater portion of 60 the pocketed steam is still lost.

My invention while contemplating the return to the cooker chamber of the pocketed steam in the inlet valve, reaches this end through the association of the inlet and outlet valves, and the passing of the pocketed steam from the receding can-empty pockets 65 of the inlet valve into the approaching can-empty pockets of the outlet valve thereby providing ample capacity for the transfer 70 of the steam and the return of practically its full volume to the cooker chamber.

To this end my invention consists in the novel improvement in a cooker which I shall now fully describe by reference to the accompanying drawings, in which—

Figure 1 is a longitudinal section, broken, of a cooker, showing its inlet and outlet valves and the by-passes between said valves.

Fig. 2 is a section on the line 2—2 of Fig. 80 1, looking in the direction of the arrows.

Fig. 3 is a section on the line 3—3 of Fig. 1, looking in the direction of the arrows.

1 indicates the box or tank of the cooker the interior structure of which with respect 85 to its can-path and means for advancing the cans therethrough, and with respect to its heating medium need not be shown, as such structure forms no part of my present invention. It is sufficient only to indicate its 90 can-inlet opening at 2 and its can outlet opening at 3.

Secured to the box at its inlet opening 2 and communicating with the interior of said box through said opening is a shell 4 which 95 at its top has an opening 5, Fig. 2, with which communicates a can-feed indicated by the chute 6. Within the shell 4 is the valve member 7, closely fitted and formed with a peripheral series of can-receiving pockets 100 7'. The valve-member 7 is carried upon and is rotated by a shaft 8, the driving connections of which need not be shown. By the rotation of the member 7, the direction of rotation being indicated in Fig. 2, by the 105 arrow, the pockets 7' successively register with the top feed opening 5 and with the inlet opening 2 into the cooker box, so that

a can fed to a pocket at the top is carried around and dropped below into the cooking chamber.

At the can outlet opening 3 of the cooker box is secured a shell 9 communicating below with the box opening 3, and at any point above with a delivery chute 10 through an opening 11, Fig. 3.

Within the shell 9 is a valve member 12, 10 closely fitted, and formed with a peripheral series of pockets 12'. This member is adapted for rotation by means of a driven shaft 13, and by its rotation, in the direction of the arrow in Fig. 3, the cans are successively passed through the opening 3, by means unnecessary to show, into successive pockets as they register with said opening and are carried up to and discharged into the delivery chute 10 through the shell opening 11.

Between the two shells 4 and 9 of the inlet and outlet valves respectively is a pipe 14. One end of this pipe opens into the shell 4 on the side within which the pockets of the 25 valve-member 7 are uprising; and the other end of the pipe opens into the shell 9 on the side within which the pockets of the valve member 12 are descending. There may be one or more of these pipes 14 separated by 30 the inter-pocket space, so that one or more pockets of the associated valves may be bypassed. I have, for illustration, shown two such pipes 14.

It will now be seen that, in operation, the 35 cans fed by the chute 6 will be carried down by the descending pockets 7' of the inlet valve member 7 and successively dropped into the cooker chamber. Each pocket as it drops its can will be filled with steam from 40 the chamber and this steam will be confined in the uprising pocket until said pocket reaches the communication with the pipe 14, whereupon the steam will pass through said pipe and enter a descending empty pocket 45 12' of the outlet valve member 12, and will by said pocket be carried down into the cooker chamber. The use of plural bypasses 14 provides for a full distribution of pressure and volume between plural pockets 50 of the associated valves.

I claim:

1. In a cooker, and in combination with its heating box, a can-feed valve and a can-discharge valve associated with said box, 55 and means for conveying fluid heating-me-

dium withdrawn from the box by the can-feed valve, into the can-discharge valve to be returned to the box by said last named valve.

2. In a cooker and in combination with its heating box, an inlet valve adapted to receive cans from without and to transfer them into said box; an outlet valve adapted to receive cans from said box and to transfer them to the outside; and a by-pass member between the two valves adapted to convey fluid heating-medium of said box, caught in the inlet valve, to the outlet valve to be returned by said last named valve into the 60 heating box.

3. In a cooker, and in combination with its heating box, a rotatable chambered inlet valve adapted to receive cans from without and to transfer them into said box; a rotatable chambered outlet valve adapted to receive cans from said box and to transfer them to the outside; and a by-pass pipe between the two valves adapted to convey fluid heating-medium of said box, caught in the 75 chamber of the inlet valve, to the chamber of the outlet valve to be returned by said last named valve into the heating box.

4. In a cooker, and in combination with its heating box, a can-inlet valve-structure 85 comprising a valve shell communicating with said box and a rotatable valve-member fitted in said shell and provided with a peripheral pocket adapted to receive and convey a can into the box; a can-outlet valve-structure comprising a valve shell communicating with said box and a rotatable valve-member fitted in said shell and provided with a peripheral pocket adapted to receive a can from the box and convey it to the outside; and a by-pass pipe connecting the shell of the inlet-valve-structure on its side in which its valve-member-pocket is receding from the box, with the shell of the outlet-valve-structure on its side in which its 95 valve-member-pocket is approaching the box, whereby fluid heating medium from the box caught in the receding can-empty pocket of the inlet valve member is conveyed to the approaching can-empty pocket of the outlet 100 valve member and returned thereby to the box.

In testimony whereof I have signed my name to this specification.

ALBERT R. THOMPSON.
